VISE FOR SLUG CASTING MACHINES

Einar G. Klingberg, Long Island City, N. Y., assignor to Intertype Corporation, Brooklyn, N. Y., a corporation of New York

Application April 29, 1935, Serial No. 18,911

19 Claims. (Cl. 199—50)

The present invention relates to improvements in typographical machines, and more particularly to line casting machines of the general class disclosed in U. S. Letters Patent No. 436,532 granted September 16, 1890 for producing type bars or slugs from character bearing matrices, wherein assembled lines of matrices, each having a character in an edge thereof, are clamped endwise between vise jaws and presented to a mold so that the character bearing portions of the matrices close the casting cavity along the front thereof, molten metal being injected into the mold to cast the type bars or slugs against the matrices and thus form printing characters on the front edges of the slugs.

The invention relates more particularly to the matrix line clamping jaws of machines of this class, and it provides novel means for mounting the jaws so that they may be readily exchanged for the purpose of substituting jaws of different forms, particularly with respect to their casting faces which cooperate with the front face of the mold.

In machines of this class, it is common practice to close the vise jaws directly against one another for the purpose of casting blank slugs against the casting faces of the jaws, and it has been proposed to provide on the casting face of one or both jaws, characters or ornamental borders against which the slugs may be cast. It has also been proposed to provide a rib projecting from the casting face of a vise jaw in position to enter the front of the mold cavity or to otherwise cooperate with the mold, as with a recess in the face thereof, to produce slugs of low-quad height.

Molds having different height casting cavities have also been employed to produce slugs in the different point sizes required in printing, and to correspond therewith, ribs of different widths are required on the vise jaws and different size characters or borders are needed. While the ribs or the characters may be provided on separable or exchangeable slides in the faces of the jaws, it has been found difficult and costly to accurately fit and securely fasten such slides into the jaw faces and much time is consumed in exchanging them. Moreover, especially in the case of ribs intended to enter within the mold cavity or into a recess adjacent thereto, it has been found impractical to obtain correct alinement of the parts to permit their proper cooperation when the mold advances in the usual manner to effect facewise and metal-tight lock up prior to casting. This difficulty arises because of variations in dif-

ferent machines and from the fact that the vise jaws, particularly if they are movably arranged for quadding and centering matrix lines, must have considerable freedom or play in their guides in order to avoid resistance to their closing and opening movements.

According to the present invention, means are provided whereby a vise jaw which is in use may be easily and quickly exchanged for another vise jaw whenever it is necessary to substitute a jaw with a different size rib or character bearing portion on its casting face and for adjusting the jaw to properly aline the rib or character bearing portion on its face with the cavity or recess in the mold. In carrying out the invention, an adjustable intermediate member is provided between the vise jaw and the usual jaw supporting block, this member being preferably carried by the supporting block and adapted to receive and locate the jaw thereon and to retain it yieldingly, as by a spring pressed locking device which is capable of release to instantly disconnect the jaw from its support and permit substitution of another jaw having a rib of different size or a casting face of different form thereon. The present invention thus overcomes the disadvantages attendant upon the use of exchangeable casting slides in the jaws and the adjustment provided for the jaw enables perfect alinement of character bearing portions or low-quad casting ribs on the faces of the jaws with the mold cavity, or with cooperative recesses in the molds, to be attained when the jaws are employed on different machines.

To these and other ends, the invention consists in certain improvements and combinations and arrangements of parts all as will be hereinafter more fully described, the features of novelty being pointed out more particularly in the claims at the end of this specification.

In the accompanying drawing: 40

Figure 1 is an elevation of a portion of a slug casting machine as viewed from the rear, the machine being equipped with automatically movable vise jaws which are provided with low-quad ribs, the jaws being detachably retained on their supports in operative positions according to the present invention by members adjustably connected to their supporting blocks;

Figure 2 is a rear elevation, partly in section and on an enlarged scale, of one of the vise jaws shown in Fig. 1;

Figure 3 is a vertical section taken on the line 3—3 in Fig. 2;

Figure 4 is a vertical section on an enlarged scale, taken on the line 4—4 in Fig. 1, and show-

55

ing a mold advanced against the jaws as usual for casting a slug; and

Figure 5 is an elevation on an enlarged scale of one of the vise jaws in Fig. 1, showing the jaw 5 partially removed from the support and retaining means provided by the present invention.

The present invention is applicable generally to slug casting machines of the class hereinbefore referred to, and the preferred embodiment of the invention is shown in the accompanying drawing and will be hereinafter described in detail. It is to be understood however that the invention is not restricted to the precise construction shown since equivalent constructions are contemplated and such will be included within the scope of the claims.

In the accompanying drawing 1 designates a portion of the usual vise frame of a slug casting machine of the class hereinbefore referred to, this frame being provided with a horizontal channel 2 to accommodate and guide supports 3 and 4 for the right hand and left hand vise jaws 5 and 6 respectively, the jaw supports in the present instance being movable longitudinally in the channel 2 to permit the jaws mounted thereon to be moved, one toward the other, as in quadding and centering. Such movement of one or both of the vise jaws may be accomplished in any suitable manner, the means shown in the present instance for effecting such movement of the vise jaws corresponding with the quadding and centering means disclosed in U. S. Letters Patent No. 1,970,527 granted August 14, 1934 to Samuel E. Sperry, to which reference is made for details of the construction and mode of operation of such jaw moving means. However, the present invention is equally applicable to fixed or movable vise jaws such as those commonly used in slug casting machines of usual and well-known forms.

As usual in machines of this class, the assembled lines of matrices are held between the inner ends of the vise jaws and presented to the front of the casting cavity 7 in a mold 8, and the mold is advanced to bring its front face 9 into contact with the casting edges of the matrices and the faces of the vise jaws, thereby closing the mold cavity at the front. If the vise jaws are provided with ribs along the portions of their casting faces which align with the mold cavity and such ribs are intended to enter the front of the mold cavity or cooperate with a recess extending along the front face of the mold adjacent to the casting cavity therein in order to reduce the height of the slug cast in the mold, the heights and widths of such ribs must be changed in order to fit into and close mold cavities or recesses of different depths or sizes, as required to produce different size low-height slugs. Likewise, if the casting faces of the jaws are provided with characters or ornamental borders or the like, these must be provided in different sizes and must be cast on slugs of different sizes.

For the purpose of illustrating one of the uses to which the present invention may be applied, both of the vise jaws 5 and 6 are provided with low-quad ribs 10 and 11 projecting outwardly or forwardly from their casting faces and adapted to enter a longitudinal recess 12 in the face 9 of the mold, as shown in Fig. 4, in order to close the front of the casting cavity 7 therein and produce low-quad slugs. Preferably, the ribs 10 and 11 are integral with the respective vise jaws, and in order to provide ribs of different heights to suit recesses in the molds of different heights,

means is provided by the present invention for readily detaching the jaws from their supports and for alining the ribs with the mold recess or with the upper and lower walls of the mold cavity if the ribs are intended to enter the front of the mold cavity rather than engage in a recess therein.

In the embodiment of the invention shown in the present instance, each of the vise jaws is provided with means for detachably mounting it on its support and for adjusting it thereon, but since such means may be of the same construction for both jaws, the same is shown in detail and will be described with reference to one of the jaws and such will suffice for an understanding of the mounting and adjustment for both of the jaws. As shown, an adaptor member 13 is provided on the jaw support 4, it being adjustably secured thereto by screws 14 and 15, and vertical adjustment of this adaptor member in relation to the support 4 is afforded by screws 16 and 17. Adjustment of the adaptor member is accomplished by loosening the clamping screws 14 and 15 after which the screws 16 and 17 which are threaded in the adaptor member 13 and back against the upper side of the jaw support 4, may be turned and set as required, tightening of the screws 14 and 15 then serving to clamp the adaptor member firmly in its vertically adjusted position on the support 4. Transverse shoulders 18 and 19, spaced longitudinally on the support 4 are arranged to cooperate with correspondingly located transverse shoulders 20 and 21 on the under side of the adaptor member 13 to aline the latter on the support 4 at the different levels to which the adaptor member is adjusted.

Means is provided for locating and retaining the vise jaw on the adaptor member, the latter being preferably provided for this purpose with a projection 22 which may extend beyond one of its ends and is preferably rounded at its top and bottom edges, and the vise jaw is provided near its matrix line engaging end with a similarly shaped recess 23 which is adapted to cooperate with the projection 22 in such a manner as to permit swinging of the vise jaw vertically, the projection 22 and recess 23 forming in effect a detachable pivotal or hinge connection between the jaw and the adaptor member. Means is provided for removably retaining the vise jaw on the adaptor member, such means comprising in the present instance a spring pressed plunger 24 having a conical head 25 at one end and a stem 26 at its other end, this plunger being guided to reciprocate in a longitudinal bore 27 formed in an upwardly extending lug 28 fixed to or formed as a part of the adaptor member 13, and the stem 26 being guided to reciprocate in a relatively smaller bore 29 formed in a lug 30 which is fixed to or formed as a part of the adaptor member. A spring 31 encircles the stem 26 and bears at one end against the lug 30 and at its other end against the plunger 24, this spring acting to yieldingly force and hold the plunger 28 normally in extended position where it is retained by a collar 32 fixed on the stem 26 and engaging the inner side of the lug 30. Suitable means is provided on the vise jaw to cooperate with the plunger 24 and thereby retain the vise jaw in its operative position on its support 4, such means comprising in the present instance a screw 33 threaded or adjustably fitted in the outer end of the vise jaw and having a conical depression 34 formed in its inner end arranged to cooperate with the conical head 25 on the

plunger 24, the inner end 35 of the screw 33 being conical to provide a bevelled surface which surrounds the depression 34 therein and is similar to the conical head 25 on the plunger 24.

5 The manner of applying the vise jaw to its adaptor member, according to the present invention, is shown clearly in Fig. 5, from which it will be seen that the vise jaw is applied by engaging the recess 23 therein over the projection 10 22 on the adaptor member and then swinging the outer end of the jaw downwardly, whereupon downward pressure on the jaw will cause the conical or bevelled surface 35 on the screw 33 to cam the plunger 24 inwardly by engagement 15 with its conical head 25, thus bringing the depression 34 in the inner end of the screw 33 into alignment and locking engagement with the conical head 25 on the plunger. In order to insure drawing of the jaw firmly into place on the 20 shoulder 22, a tapered pin 36 may be fixed in the upper wall of a recess 37 provided in the jaw to accommodate the locking plunger 24, this tapered pin being arranged to engage against the lug 30 as the outer end of the jaw is swung 25 into locked position, and in order to position the jaw laterally on the adaptor member, longitudinally extending shoulders 39 are provided along the front and rear sides of the adaptor member, these shoulders engaging the inner side 30 walls of the recess 37 of the jaw as the latter moves into its locked position, thereby alining the face 39 of the adaptor member with the casting face 40 of the vise jaw.

The plunger 24 and screw 33 thus comprise 35 cooperating parts to yieldingly and removably lock and retain the vise jaw firmly on the adaptor member and to permit removal of the jaw merely by forcing its outer end upwardly to disengage the screw from the plunger. The invention thus 40 provides means for mounting a vise jaw for pivotal movement relative to its support and locking means releasable upon such pivotal movement of the jaw to enable disconnection of the jaw from its support for the purpose of 45 changing the jaw for another jaw of different form, and an adjustable adaptor member for locating and retaining the jaw on its support, which enables the jaw to be mounted thereon in proper vertical alinement on different machines 50 and in such position of alinement as to assure accurate engagement of a rib projecting from the casting face of the jaw with a recess in the face of the mold with which it cooperates during a slug casting operation.

55 I claim as my invention:—

1. In a slug casting machine having a vise, a vise jaw support mounted thereon, and means for mounting a vise jaw on said support at different levels.

60 2. In a slug casting machine having a vise and a vise jaw support mounted thereon, means mounted on said support for retaining a vise jaw in fixed relation thereto at different levels.

3. In a slug casting machine having a vise and a vise jaw support mounted thereon, an adaptor on said support having means for yieldingly locking a vise jaw thereon against longitudinal and vertical displacement.

4. In a slug casting machine having a vise and a vise jaw support mounted thereon, an adaptor 70 adjustably mounted on said support, and means on the adaptor to engage a vise jaw and yieldingly retain said jaw in fixed relation thereto.

5. In a slug casting machine having a vise jaw 75 support and a vise jaw removably mounted

thereon, locking means operative by vertical movement of the jaw to release the locking means for removal of the jaw from the jaw support.

6. In a slug casting machine having a vise jaw support and a vise jaw connected thereto for vertical pivotal movement, locking means yieldable upon pivoting the jaw to permit disconnection of the latter from the jaw support. 5

7. In a slug casting machine having a pair of vise jaws, a movable support for each jaw, said supports having adjustable means thereon for connecting the respective jaws thereto at different levels. 10

8. In a slug casting machine having a pair of vise jaws, movable supports for said jaws having 15 adjustable means thereon engageable with the respective jaws for mounting them on said supports at different levels, and means for yieldingly locking the jaws in engaged relation respectively with said adjustable means. 20

9. In a slug casting machine having a vise, a vise jaw support mounted thereon, and a vise jaw, adjustable means on said support having means engageable with the vise jaw to locate and retain it at different levels relative to the support, and means on the vise jaw engageable with the support to retain the jaw longitudinally of the support and said adjustable means thereon. 25

10. In a slug casting machine having a pair of vise jaws, movable supports for said jaws, adjustable means engageable with the respective jaws and their supports for positioning the jaws relative to their supports at different levels, and means for yieldingly connecting the jaws to their supports at different adjusted positions. 30

11. In a slug casting machine having a vise, a vise jaw support mounted thereon, and a vise jaw, vertically adjustable means on said support for receiving and retaining the vise jaw, said adjustable means and jaw having pivotally engageable connections between them to permit rocking the jaw into and out of engagement with the support. 35

12. In a slug casting machine, a vise comprising a vise jaw support, a vise jaw, a member having means guiding it for vertical adjustment on said support, and means for removably retaining the vise jaw on said member. 45

13. In a slug casting machine, a vise comprising a vise jaw support, a vise jaw, a member 50 guided for vertical adjustment on said support and held against longitudinal displacement thereon, means for securing said member in different vertically adjusted positions on said support, and means for removably retaining the vise jaw on 55 said member.

14. In a slug casting machine, a vise comprising a vise jaw support, a vise jaw, means for detachably and pivotally connecting the jaw adjacent to one end thereof to said support, and 60 means adjacent to the other end of the jaw for holding the latter in predetermined position on said support.

15. In or for a slug casting machine, a vise jaw having a casting face, a vise jaw support, and an 65 interposed member having means for removably mounting the vise jaw thereon and means for adjusting it on said support to adjust the jaw in the plane of its casting face.

16. In or for a slug casting machine, a vise jaw 70 having a casting face, a vise jaw support, a member having means for pivotally attaching the jaw thereto for swinging movement in the plane of its casting face, and means for mounting said member in different adjusted positions on said 75

- support to adjust the position of the jaw on said support in the direction of the plane of its casting face and transversely of the length of the jaw.
5. 17. In a slug casting machine having a mold, a vise for holding a matrix line in casting relation to the mold comprising a vise jaw support, and means on said support adapted to exchangeably receive different vise jaws and to adjust them into alinement with the mold.
10. 18. In a slug casting machine having a mold, a vise for holding a matrix line in casting relation to the mold comprising a vise jaw support, a vise jaw movable longitudinally of the mold and having a casting face to engage the mold, and means for mounting the vise jaw on said support for adjustment thereon in a direction transversely of its direction of movement and parallel to the plane of its casting face.
5. 19. In a slug casting machine having a vise jaw support and a vise jaw mounted thereon for pivotal movement relative thereto, locking means for retaining the jaw on the jaw support and releasable by pivotal movement of the jaw to permit 10 connection and disconnection of the jaw with respect to the jaw support.

EINAR G. KLINGBERG.
